UNITED STATES PATENT OFFICE.

SAMUEL E. SHEPPARD, OF ROCHESTER, NEW YORK, ASSIGNOR TO EASTMAN KODAK COMPANY, OF ROCHESTER, NEW YORK, A CORPORATION OF NEW YORK.

FLUORESCENT X-RAY SCREEN.

Application filed January 24, 1925. Serial No. 4,562.

This invention relates to intensifying screens for X-ray purposes and more particularly to a screen the active layer of which is made with such a low percentage of binder that it would ordinarily be quite too fragile for practical use.

In U. S. Patent No. 1,532,782, granted April 7, 1925, to Leon W. Eberlin and myself, there is described an X-ray screen comprising an intermediate active layer with protective and supporting layers upon the opposite sides thereof. The active layer is there described as comprising a fluorescent salt and a very small proportion of binder, less than 5% and preferably of the order of 1 to 2%, by weight of the salt. When the active layers of screens made by that process contain 2% or more of binder they are sufficiently rugged to stand any ordinary use. When, however, they have substantially less than 2%, say about 1% or less, of binder, they are still sufficiently rugged to withstand the manipulations of manufacture and of careful usage, but they are too fragile for any careless treatment and are very liable to accidental damage. For instance, a screen containing only 1% of binder in the active layer and ten or twelve inches across should be lifted by holding the opposite edges in both hands. If it is lifted by one corner, cracks are very likely to appear in the active layer which cannot stand the flexure caused by the weight of the screen. A screen made by our process and containing 2% of binder in the active layer can be lifted by one corner and the flexure does no damage. Of course, in any case the screen as a whole does not break or crack because of the strong flexible outside layers, but the active layer within may show cracks under such treatment.

It is, of course, desirable that the percentage of binder should be low since the efficiency increases with the proportion of the active salt. The object of the present invention is to improve such a screen by increasing the percentage of fluorescent salt and by strengthening the screen so that it is more rugged and capable of use without extreme care. I accomplish this and other objects by using around the edge of the screen a metal binder rendering the screen less flexible and more rugged, the details of this binder and the method of applying it to the screen being described hereinafter and illus-

tated in the accompanying drawings, in which;

Fig. 1, is a perspective view of my improved screen;

Fig. 2, is a greatly enlarged fragmentary view showing the binder before application to the screen;

Figs. 3, and 4, are similar fragmentary views showing binders of slightly different finished form in place on the screen.

The screen proper is designated 1 and, like the screens described in the above mentioned patent, comprises a front very thin, protective layer 2, and intermediate active layer 3, and a rear protecting and supporting layer 4, these being formed in the manner fully described in the patent.

The active layer, however, has an exceptionally low percentage of binder, substantially less than 2% and preferably less than 1%, the formula to be otherwise that given in the patent. Such a layer alone could hardly be handled or used at all, but can be made and used, if handled carefully, when made in accordance with the improved methods described in said patent.

This screen material with its three layers is formed in large sheets on a glass table or the like from which it is stripped and cut into such sizes as are desired for use. These individual cut screens are then bound at the edges with metal strips 5.

A thin metal strip which may be of brass, bent into an open U in cross section as shown in Fig. 2, is laid along the edge of the cut screen with its bend 6 spaced as shown at 7 from the actual edge 8 of the screen, and the branches 9 lying on opposite sides of the screen.

The branches 9 are then subjected to considerable pressure, preferably in a suitable machine not constituting a part of the present invention, and are bent into intimate contact with the screen, as in the forms shown in Figs. 3 and 4.

In Fig. 3, the branches 9 are shown as forced below the surfaces of the screen, as shown at 10, leaving the bend as an edge beading 11, the thickness of which is the same as the thickness of the original screen 1. The material of the screen where subjected to pressure is forced or caused to flow into the bead 11.

In Fig. 4, the branches 9 are shown as having been forced in sufficiently to bring

their outer surfaces flush with the surfaces of the screen, the material of which is forced out, substantially filling the space 7 in the bend 6.

5. The screen can now be used with its front surface in contact with a sensitive plate or film in the usual way. As the front layer 2 is extremely thin, the highly efficient fluorescent layer 3 is positioned very close to

10 the sensitized emulsion.

The binder, while not rigid, furnishes sufficient support to the screen to keep it from flexing freely and the fragile layer 3 is not submitted to the bending stresses that would

15 tend to crack it.

It is to be understood that the embodiments here disclosed are by way of example and that I contemplate as within the scope of my invention all such modifications and equivalents as fall within the terms of the

20 appended claims.

Having thus described my invention what I claim is new and desire to secure by Letters Patent is:

25 1. An X-ray screen in sheet form comprising a fragile active layer of which at least ninety-eight percent by weight is fluorescent salts and having around its border a reinforcing strip of sufficient stiffness to prevent damaging flexure of such sheet.

30 2. An X-ray screen in sheet form comprising a fragile active layer of which at least ninety-eight percent by weight is composed of fluorescent salts and having its edges bound with a reinforcing metal strip.

35 3. An X-ray screen in sheet form comprising a fragile active layer of which at least ninety-eight percent by weight is composed of fluorescent salts and an edge binding comprising a channel shaped sheet

metal strip embracing the borders of the screen.

4. An X-ray screen in the form of a rectangular sheet and comprising a fragile active layer of which at least ninety-nine percent by weight is composed of fluorescent salts, and having around its border a reinforcing strip of sufficient stiffness to prevent damaging flexure of such sheet.

5. An X-ray screen in the form of a flexible rectangular sheet and comprising a fragile active layer, of which at least ninety-nine percent by weight is composed of fluorescent salts and flexible protective layers on each side of the active layers, and a reinforcing edge binding comprising a channel shaped sheet metal strip embracing the borders of the screen.

6. An X-ray screen in the form of a flexible rectangular sheet and comprising an active layer of which over ninety-nine percent by weight is composed of fluorescent salts, and flexible protective layers on each side of the active layers, and a metal binding strip embracing the margins of the sheet and lying within the planes determined by the outer surfaces of the sheet.

7. An X-ray screen in the form of a flexible rectangular sheet, and comprising an active layer, and having around its border a reinforcing strip of sufficient stiffness to prevent damaging flexure to the screen, the percentage by weight of fluorescent salts in the active layer being so high that the screen would be too fragile for ordinary usage without such reinforcing strip.

Signed at Rochester, New York, this 20th day of January 1925.

SAMUEL E. SHEPPARD.
